[57] CLAIM

The ornamental design for handle, as shown and described.

DESCRIPTION

FIG. 1 is a perspective view of our new design of a handle; FIG. 2 is a front elevational view of our new design of the handle; a rear elevational view, a right side elevational view and a left side elevational view being the same as the front elevational view;

FIG. 3 is a top plan view of our new design of the handle; FIG. 4 is a bottom plan view of our new design of the handle; and,

FIG. 5 is a cross-sectional view taken along line 5—5 of FIG. 3 showing certain aspects of our new design of the handle.
